UNITED STATES PATENT OFFICE.

DAVID C. BETTISON, OF OMAHA, NEBRASKA.

WRENCH.

1,419,659.

Specification of Letters Patent. Patented June 13, 1922.

Application filed October 31, 1921. Serial No. 511,678.

To all whom it may concern:

Be it known that I, DAVID C. BETTISON, a citizen of the United States, and a resident of Omaha, in the county of Douglas 5 and State of Nebraska, have invented certain new and useful Improvements in Wrenches, of which the following is a specification.

My invention relates particularly to solid

10 or one-piece wrenches for use on square nuts. It is the object of my invention to provide a wrench of this class adapted to produce automatically a ratchet-like action, or having means whereby in the use of the wrench 15 it is merely necessary to move the handle reciprocatingly, oscillating the same about the axis of the bolt, in order to rotate the nut intermittently in one direction. The ratchet-action referred to is attained by the 20 peculiar form and proportions of the wrench-jaws, which firmly engage the nut as the wrench is moved in one direction, while by movement in the opposite direction the nut is at once released and remains 25 stationary, the jaws sliding freely about the same until they are in position to engage the succeeding pair of nut-faces and grip the same to again advance the nut in the desired direction. More particular objects 30 of my invention are to so form and proportion the wrench-jaws as to readily accommodate therein nuts having the usual variations from the standard or nominal size with which the wrench is intended for use; 35 to so shape and proportion the jaws as to secure the immediate release of the nut at the beginning of the backward or idle stroke of the wrench; to so form and proportion the jaws as to secure a relatively 40 large working surface thereon for engagement with the nut-faces, and so that moderate wear of the working faces may occur without interfering with the operation of the wrench; and to so arrange the jaws relatively 45 to the handle that during the forward or working stroke the force applied upon the handle will tend to hold the head and jaws against the nut rather than to disengage the same therefrom or to permit slip- 50 page between the jaws and nut-faces.

In the accompanying drawings Fig. 1 is a side view of a wrench embodying my invention, Fig. 2 is a front edge view of the same, Fig. 3 is a side view of the 55 wrench-head, drawn on a larger scale than

Figs. 1 and 2, and showing the relation of the jaws to a nut of normal size, Fig. 4 is a similar view showing the relation of the jaws to the maximum and minimum sizes of nuts which may be held therein, 60 and Figs. 5, 6 and 7 are side views showing successive relations of the jaws and a nut during the reverse or idle stroke of the wrench.

In the illustrated embodiment of my invention I provide a relatively long handle 8 which at its upper end is of circular cross-section and is conically tapered or gradually enlarged from said end toward the main body. The main body of the handle is of 70 substantially uniform thickness throughout, the front and rear edges being rounded, the sides flat, and the width gradually increased from the conically tapered end-portion toward the head 9. The latter is 75 a bulbous enlargement in the plane of the flat sides of the handle, the rounded edges of the latter being continued about the head nearly to the ends of the jaws. The rear jaw 10 is relatively short, the inner or 80 working face 11 of said jaw being a plane surface of which the length is approximately three-sevenths of the length of one of the side-faces of the nut A with which the wrench is to be used. The end 12 of 85 the throat or space between the jaws is also a plane-surface, which is at a right angle to the jaw-face 11, the angle α indicated in Fig. 3 being 270° . The front jaw 13 is of about the same length as one side of the 90 nut A, and at the inner side of said jaw, adjoining the end thereof, there is a plane-surfaced working face 14 of which the length is substantially the same as that of the working face 11 of the rear jaw. From 95 the end of said working face 14 the jaw is slightly hollowed or recessed to provide a clearance-space which extends to the juncture of the jaw with the end-face 12 of the throat. The hollowed or recessed face-portion 15 is slightly curved or arcuate, and throughout its length is spaced from the plane defined by extension or prolongation of the working-face inwardly of the throat to the end-surface 12. The form of 100 105 the curved or recessed face 15 shown in the drawings provides the minimum clearance desirable for a proper operation of the wrench, and an increased clearance will not affect the operation thereof, but will 110

either weaken the jaw 13 or necessitate enlargement of the head by added material at the outer edge of the front jaw.

The working faces 11 and 14 are not parallel with each other, but are slightly convergent outwardly of the throat. Thus, the working face 14, as shown in the drawings, is at an angle of 30° to the longitudinal axis or center-line of the handle 8, said angle being indicated at y in Fig. 1; while the working face 11 is at a slightly greater angle, or about 33° , to the handle 8. The angular difference between the faces 11 and 14 is indicated at z in Fig. 3, wherein the line a is parallel with the face 14, and the line b is in the extended plane of the face 11.

The jaws are so proportioned that the nut A, of the normal size for which the wrench is intended for use, will fit therein as shown in Fig. 3, in which it will be noted that the working face 14 fits squarely against one side of the nut, while the opposite side of the nut is engaged by the point or outermost edge of the face 11. It will also be seen that the inner side of the nut, which adjoins the face 12, contacts with said face 12 only at that corner of the nut which is adjacent to the face 11, and said inner side of the nut is at an angle to the face 12 the same as the angle between the jaw-faces 11 and 14. Referring to Fig. 4, an under-size nut is indicated by the dotted lines A', and an oversize nut A'' is shown in full lines. It will be seen that the nut A' fits squarely against the faces 11 and 12, while the front side of said nut, at the lower corner thereof, engages the working face 14. With the oversize nut A'', the upper and rear faces are engaged similarly to the normal nut A, the angle between the nut-faces and the faces 11 and 12 being slightly greater than with the normal sized nut A. The upper front corner of the oversize nut A'' extends somewhat into the clearance-space provided by the curved jaw-face 15, and the front side of the nut is engaged by the corner formed at the juncture of the face-portions 14 and 15.

In the operation of the wrench, after the nut is engaged by the jaws, as shown in Fig. 3, a forward pull upon the wrench-handle exerted transversely to the axis thereof is in the direction of the arrow c in Fig. 1, while the direction which the wrench-head would be required to move in order to become disengaged from the nut, is indicated by the arrow d in the same figure. Obviously, as the two directions differ by the angle m , or about 120° , there is no possibility of the wrench becoming disengaged from the nut during the forward pull thereon.

Referring now to Figs. 5, 6 and 7, the operation of the wrench during the reverse or idle stroke thereof will be clearly ap-

parent. At the beginning of said movement 65 the nut is instantly released as it moves (relatively to the wrench) into the clearance-space provided by the curved face 15 of the front jaw. The weight of the wrench rests upon the upper corner of the nut, where the same engages the end-face 12 of the throat, and the nut is also engaged by the rear jaw at the corner or outer end of the jaw-face 11, while the front jaw swings clear of the nut, as indicated in Fig. 5. Further rearward 70 movement of the wrench brings the same into the relation to the nut shown in Fig. 6, at which the corner at the juncture of the faces 14 and 15 passes the front corner of the nut. Thereafter the nut is engaged by 75 the working face 14 of the front jaw and the end of the rear jaw, and the upper corner of the nut is no longer engaged with the end-face 12. The locus or path of said upper corner of the nut, relative to the face 12, 80 is indicated by the dotted line n in Fig. 7, from which it will be seen that slightly less than one-half of the whole length of said face 12 is utilized in the operation, and that the portion of the face 12 between its junction with the curved face 15 and the point of tangency of the line n therewith might be hollowed out or recessed, without affecting the operation. That portion of the face 12 85 adjacent to the rear jaw-face 11, and extending from said face 11 to the point of tangency on the line n , is essential, however, to the proper operation of the wrench. The said portion of the face 12 forms, first, a stop or abutment which limits the entrance 90 of the nut into the throat of the wrench; and, second, by the engagement of the upper corner of the nut with said surface, during the first portion of the reverse or idle stroke of the wrench, the latter is quickly 95 lifted or moved outwardly from the axis of the nut, whereby to cause the front jaw 13 to swing clear from the front corner of the nut in the shortest possible portion of the stroke. It will be seen that, from the relative position of the nut and wrench shown 100 in Fig. 7, a slight further rearward movement of the wrench will bring the same into position to slip down over the nut into the same relation thereto as shown in Fig. 3, 105 from which the forward or working stroke may be made.

While I have shown in the drawings, and have herein referred only to a wrench intended for use on nuts of one size, with such variations from the standard or nominal size as are likely to occur in commercial practice, it will be obvious that my invention may be embodied in a double-end wrench, having 110 heads at each end of the handle, and with the jaws of said heads proportioned for use on nuts of two distinctly different sizes.

Now, having described my invention, what

I claim and desire to secure by Letters Patent is:

1. A wrench of the class described, comprising an integral handle and head, the latter having fixed jaws with spaced plane-surfaced working faces convergent outwardly of the throat-space between them, one of said jaws of a length less than one-half the length of the other, the latter jaw being of a length approximately the width of the throat-space, the end of the throat-space adjacent to the shorter jaw being a plane surface extending at a right angle to the working face of said jaw, the working face of the longer jaw extending from the end thereof less than half way to the end of the throat-space, and the remaining portion of the face of said jaw being recessed to provide a clearance-space opposite the working face of the short jaw.
2. A wrench for square nuts, comprising a head having a long and a short jaw integral therewith, said jaws spaced apart to form a throat-space between them, the short jaw having a plane-surfaced working face adjoining the end of said throat-space, said end of the throat-space adjoining said jaw extending substantially at a right angle to said working face, the long jaw having a plane-surfaced working face spaced from the end of the throat-space and said jaw being recessed between said working face and the end of the throat-space to provide clearance between said portion of the jaw and the side of a nut engaged by the working face of the jaw, and said plane-surfaced working faces of the jaws being convergent outwardly of the throat-space.
3. A one-piece ratchet-wrench for square nuts, comprising a handle and a head having a short jaw and a long jaw, said jaws spaced to provide a throat-space between them, the end-face of said throat-space adjacent to the short jaw being at a right angle to the working face of said jaw, the long jaw having a working face spaced from the end of the throat-space, the face of the long jaw adjoining the end of the throat-space being recessed to provide a clearance between the same and the side of a nut engaged with said working face of said jaw, the working faces of the jaws converging outwardly of the throat-space, and said working faces being disposed at an angle to the longitudinal axis of the handle such that an actuating force exerted transversely to said axis of the handle and toward the long jaw will tend to move the head toward a nut held between the jaws.

DAVID C. BETTISON.
